CLAIM

The ornamental design for a pharmaceutical tablet, as shown and described.

DESCRIPTION

FIG. 1 is a perspective view of the pharmaceutical tablet according to an embodiment of the present invention as viewed from the bottom and to the right of the tablet;
FIG. 2 is a perspective view of the pharmaceutical tablet as viewed from the top and to the left of the tablet;
FIG. 3 is a front plan view of the pharmaceutical tablet which includes broken line markings for a cross-sectional plane axis 9-9;
FIG. 4 is a rear plan view of the pharmaceutical tablet;
FIG. 5 is a left side view of the pharmaceutical tablet;
FIG. 6 is a right side view of the pharmaceutical tablet b
FIG. 7 is a bottom view of the pharmaceutical tablet;
FIG. 8 is a top of the pharmaceutical tablet; and,
FIG. 9 is a cross-sectional view of the pharmaceutical tablet taken along axis 9-9 in FIG. 3.

The broken line marked 9-9 in FIG. 3 refers to a cross-sectional plane for FIG. 9 and forms no part of the claimed invention.
